UNITED STATES PATENT OFFICE.

CHARLES GILBERT HAWLEY, OF CHICAGO, ILLINOIS, ASSIGNOR, BY MESNE ASSIGNMENTS, TO CENTRIFIX CORPORATION, OF CLEVELAND, OHIO, A CORPORATION OF DELAWARE.

CENTRIFUGAL FIXTURE.

Application filed November 28, 1924. Serial No. 752,721.

To all whom it may concern:

Be it known that I, CHARLES GILBERT HAWLEY, a citizen of the United States, residing at Chicago, Cook County, Illinois, 5 have invented certain new and useful Improvements entitled Centrifugal Fixtures, of which the following is a specification.

In all processes of distillation and evaporation, and throughout the arts of fluid 10 purification and rectification, as by separators, it is both assumed and desired that the fluid evolved or treated shall leave the drum or container in a pure state, free from foreign substances, such as heavier liquids 15 and solids. But as a rule the conditions controlling and modifying the operation in some measure defeat this primary expectation and purpose, and eventuate in producing or permitting the escape of impure 20 fluids.

The objects of the invention are to perfect such processes of purification and to provide a simple and reliable device or apparatus for the performance of the perfected process. These objects and the specific 25 character of the invention will presently appear in further detail.

The invention will be readily understood on reference to the drawings that form part 30 of this specification, in which:

Fig. 1 is a vertical cross-section of a steam boiler drum, or the like, equipped with a centrifugal fixture embodying this invention. Fig. 2 is a top view of a centrifugal fixture partly in section on the line 2—2 of 35 Fig. 1. Fig. 3 is a horizontal section on the line 3—3 of Fig. 1 and Figs. 4 and 5 illustrate modified forms of the tuyère ring portion of the novel fixture.

Referring to Fig. 1, 1 represents the pressure drum, 2 the liquid level therein, 3 the outlet opening and 4 the nozzle proper. It will be understood that the offtake pipe joins the nozzle. The end of the drum contains 45 the usual man-head 1'. But for the presence of the novel apparatus comprising this invention, the fluid or vapor leaving the steam or other space 5 would pass directly to the nozzle 4. Instead, this novel apparatus, 50 though composed of parts all of which are stationary, that is non-rotative, subjects the escaping fluid to a rapid whirling action. In consequence of this rapid whirling action substances heavier than the fluid are effectively separated therefrom and either re-

turned to the drum, or separately discharged therefrom if it be desired to rid the drum thereof.

In its best form the apparatus comprises 60 two main portions, to wit, the top member 6 and the bottom member 7. The upper part of the member 7 fits into the bottom of the member 6 and most conveniently the parts are fixedly, though separably, attached 65 one to the other as by means of a plurality of bolts (not shown). It may be at once explained that as the parts must needs be introduced through the manhole they must be of a size to permit such introduction. The device as a whole primarily takes its 70 size from that of the outlet 3 to be served. Manholes are of standard size. The smaller sizes of this apparatus may be introduced intact, but the larger sizes must be made 75 in separate parts, and devices of the largest sizes, though rarely requiring top members 80 6 which are made in two parts, usually are fitted with lower parts, i. e. tuyère rings 7 which, for convenience of introduction, are made in two parts.

The top member 6 is of annular ring-like formation containing the annular race 6^a, having the tangential peripheral outlet 6^b. At the top of the member 6 is the central outlet 6^c, which is joined to the boiler nozzle by the nipple 8. The latter may serve as 85 a support for the centrifugal fixture. The bottom of the race member contains the large central opening 6^d. As shown, the annular race proper is peripherally of larger 90 diameter than the opening 6^d. To the bottom of the race member is attached the multiply tuyère ring 7. This is characterized by an annular series of tangentially 95 positioned tuyère blades 7^a, between which are the tangential tuyères 7^b. At the lower ends of the blades is a bottom or floor 7^b, containing a sink or central cavity 7^c. Above the cavity and said larger diameter 100 is a false bottom or circular plate 7^d peripherally separated by a plurality of short posts 7^e. The narrow annular opening 7^f between the plate 7^d and the bottom 7^b has a distinct function about to be described. A drain pipe 9 leads from the bottom of the cavity 7^c and another drain pipe 10 leads 105 downward or outward from the discharge nozzle 6^d of the race member. These pipes 9 and 10 may terminate short of the bottom of the drum 1 or they may lead outward 110

through the shell of the drum, there to be connected with a common trap or with individual discharge traps. Such traps are employed when it is desired to remove from the drum the moisture or other impurities which the described centrifugal fixture serves to separate from the fluid seeking escape at the outlet 6^c.

To exemplify the invention by referring 10 it to a steam boiler, it may be assumed that the drum 1 is a steam drum of an active steam boiler and partly filled with steam seeking escape at the boiler nozzle. To 15 reach the boiler nozzle the steam obviously must pass between the tangentially positioned tuyère blades 7^a, that is through the tangential slot-like tuyères 7^x. Entering the tuyère ring in this manner the streams join in a very rapid rotative motion within 20 the tuyère ring and superimposed race. In consequence of the manner of entrance and of the rapid rotation moisture globules and particles of solid matter are separated and retained upon the inner periphery of the 25 whirling stream, that is upon the inner periphery of the tuyère ring. As the bottom 7^b prevents downward movement of the steam it moves upward toward the outlet. Thus the collected impurities are carried into 30 the race. On reaching the top of the tuyère ring the whirling impurities are permitted to expand or move outward and thus they are quickly removed from the influence of the main whirling body of steam. As quickly, the impurities find escape through the 35 nozzle 6^b and the pipe 10. I have thus described the operation of the device in order that its principal action may be clearly understood. There is a further action, however, 40 which is of much importance and which is related to the novel structure of the bottom of the tuyère ring or member 7. While there can be no perceptible movement of the steam within the tuyère ring and toward the bottom, there is nevertheless a 45 tendency toward such movement and by reason of that tendency a portion of the impurities entering with the steam tend to collect in the lower inner corner of the tuyère. Lest these perchance find opportunity to 50 spread across the floor or bottom of the tuyère and thus enter the vortex at the axis thereof, I resort to the bottom structure illustrated. Obviously the impurities which 55 reach and lodge upon the floor 7^b are displaced inwardly and thus are dumped into the cavity 7^c. From that cavity they drain away through the pipe 9 and thereby such 60 impurities are effectually prevented from re-entering the stream of steam seeking escape at the central outlet of the fixture.

Fig. 4 illustrates a modified construction in which the tuyère bottom 7^c is provided with a plurality of dump openings 7^h at its periphery, that is, closely adjacent to the 65 feet of the tuyère blades. These openings communicate with the underlying cavity 7ⁱ, having a drain pipe for emptying it.

Fig. 5 illustrates a further modification in which a shallow groove 7^j is provided in 70 the tuyère bottom 7^k. In that case the groove is provided with a tangential peripheral outlet 7^l. The operation is much as before described.

Fig. 5 incidentally discloses a preferred 75 form of tuyère ring top presenting an overhanging annular abutment 7^m, which performs the function of enforcing the discharge of a greater portion of the impurities through the bottom of the tuyère.

The described tuyère bottoms effectually 80 take care of slugs of water that may enter the centrifugal fixture, quickly discharging such excess quantities and relieving the upper portion of the fixture of the burden of carrying for them.

As various modifications of the invention 85 will readily suggest themselves to others, I desire it to be understood that this invention is not limited to the precise structures shown and that such structures be regarded as merely exemplary of the invention.

The following claims will make clear the 90 fact that the invention is not limited to the specific structures finding illustration in the drawings.

Having thus described my invention, I claim as new and desire to secure by Letters Patent:

1. A centrifugal liquid purifying device 100 comprising an annular race member having a peripheral discharge and a large central outlet, in combination with a multiply tuyère ring adapted to direct the fluid whirlingly into said race and toward said outlet, said ring having a bottom containing a cavity to receive impurities not elevated to said race.

2. The herein described multiply tuyère ring having a bottom containing a central cavity and a superimposed false bottom plate spaced about the same substantially as and for the purposes specified.

3. The herein described multiply tuyère ring presenting a bottom or end containing a 115 ring-like opening, an underlying cavity portion and means for discharging collected impurities therefrom.

In testimony whereof, I have hereunto set my hand this 24th day of November, A. D. 120 1924.

CHARLES GILBERT HAWLEY.
